FLUID PRESSURE CONTROL

Ransom Tyler, Greenfield, Wis., assignor to The Oilgear Company, Milwaukee, Wis., a corporation of Wisconsin

Application September 26, 1938, Serial No. 231,688

13 Claims. (Cl. 60—52)

This invention relates to apparatus for controlling the pressure in a fluid circuit, and it is particularly adapted for controlling the pressure of the liquid employed to operate hydraulic presses and the like.

An object of the invention is to provide a control by means of which the pressure in a fluid circuit may be gradually varied through a predetermined range during a predetermined period of time.

Another object is to provide a control by means of which the pressure in a fluid circuit may be gradually varied through a predetermined range during each cycle of operation of the control and which will have the working parts thereof in position to start another cycle at the completion of each cycle.

Another object is to provide a control for gradually varying the pressure in a fluid circuit through a predetermined range first at one rate and then at a different rate.

Another object is to provide a control of the above described character which is positive and precise in operation.

Other objects and advantages will appear from the description hereinafter given of a control in which the invention is embodied.

The invention is exemplified by the control shown schematically in accompanying drawing 30 in which the views are as follows:

Fig. 1 is a diagrammatic view showing a hydraulic press provided with a control in which the invention is embodied.

Fig. 2 is a view showing a selector valve in a position different from that shown in Fig. 1.

Figs. 3 and 4 are views showing a reversing valve in positions different from that shown in Fig. 1.

For the purpose of illustration, a control embodying the invention has been shown applied to a hydraulic press which is employed to compress material having a high liquid content but the invention is not limited to such use.

Since the press per se forms no part of the present invention, it has been represented by a stationary lower die or mold 1 which is open at its top and is provided adjacent its bottom wall with a plurality of small drainage apertures 2, a movable upper die 3 which is so proportioned as to closely fit the interior of mold 1, a stationary cylinder 4, a piston 5 which is closely fitted in cylinder 4 and connected by a rod 6 to die 3 to move it into and out of mold 1, a pump 7 which energizes motor 4—5 and which draws liquid from a reservoir 8 and discharges it into

a supply channel 9, and a reversing valve 10 which is arranged in a valve casing 11 and controls the flow of liquid to and from motor 4—5.

Reversing valve 10 has two spaced apart heads or pistons formed thereon and closely fitted in the bore 12 of casing 11. Bore 12 has three annular grooves or ports 14, 15, and 16 formed in its side wall and its upper end is connected by a channel 17 to a channel 18 which communicates with the lower end of bore 12 and discharges into reservoir 8.

Port 14 is arranged between the other two ports and has supply channel 9 connected thereto. Port 15 is controlled by and is narrower than the lower piston on valve 10 and is connected by a channel 19 to the lower end of cylinder 4. Port 16 is controlled by and is wider than the upper piston on valve 10 and is connected by channel 20 to the upper end of cylinder 4.

When valve 10 is in the position shown in Fig. 1, the wide lower piston on valve 10 blocks port 15 so that piston 5 and die 3 are supported by the liquid trapped in the lower end of cylinder 4, and the narrow upper piston on valve 10 is positioned between the edges of wide port 16 so that the liquid discharged by pump 7 may flow through channel 9, bore 12 and channels 17 and 18 into reservoir 8.

When valve 10 is moved downward to the limit of its movement as shown in Fig. 4, port 15 is open to port 14 so that liquid from pump 7 may flow through channel 9, bore 12 and channel 19 to the lower end of cylinder 4 and raise piston 5 and die 3, and port 16 is open to channel 17 so that liquid ejected from the upper end of cylinder 4 by piston 5 during its upward movement may flow through channel 20, bore 12 and channels 17 and 18 into reservoir 8.

When valve 10 is moved upward to the limit of its movement as shown in Fig. 3, port 16 is open to port 14 so that liquid from pump 7 may flow through channel 9, bore 12 and channel 20 to the upper end of cylinder 4 and move piston 5 downward, and port 15 is open to channel 18 so that liquid ejected from the lower end of cylinder 4 by piston 5 during its downward movement may flow through channel 19, bore 12 and channel 18 to the reservoir 8.

If mold 1 contains a quantity of material from which liquid is to be pressed as the material is compressed by die 3, the pressing force exerted by die 3 should be gradually varied from an initial minimum to an ultimate maximum in order that the liquid content of the material may be

gradually eliminated and the material pressed into a substantially solid cake or slab having certain desired characteristics.

This is accomplished by permitting a part of 5 the liquid discharged by the pump to escape through a relief valve and by adjusting the valve to gradually increase the resistance thereof so that pump pressure is gradually increased with a resultant gradual increase in the pressing force 10 exerted by die 3 upon the material in mold 1.

If but one relief valve were employed, it would be necessary to readjust it after each pressing operation before another pressing operation could be started. In order to avoid such a delay and 15

15 the necessity of manual adjustment of the relief valve, two relief valves are provided and the resistance of one is decreased while the resistance of the other is being increased, and communication is blocked between the pump and the relief 20 valve having the lower resistance during the time that the resistance of the other relief valve is being increased.

As shown, the control is provided with a low 25 pressure relief valve 25 and a high pressure relief valve 26 the resistances of which are simultaneously varied inversely to each other as will presently appear. High pressure relief valve 26 may have its inlet connected directly to supply channel 9 by a channel 27 but communication 30 between low pressure relief valve 25 and channel 9 is controlled by a selector valve 28 which has two heads or pistons formed thereon and closely fitted in the bore 29 of a valve casing 30.

Bore 29 has two annular grooves or ports 31 35 and 32 formed in its wall and both of its ends connected to a drain channel 33 which discharges into reservoir 8. Port 31 is connected to supply channel 9 by a channel 34, and port 32 is connected to the inlet of relief valve 25 by a channel 36.

Selector valve 28 may be operated in any suitable 40 manner but it has been shown as being urged toward the right by a spring 36 arranged in one end of bore 29 and as being adapted to 45 be moved toward the left by a solenoid 37 having its core connected to the stem of valve 28 and its winding connected to a control panel 38 by conductors arranged in a cable 39.

The liquid exhausted from supply channel 9 50 through relief valve 25 or relief valve 26 is discharged into reservoir 8 through channels arranged in any suitable manner. For example, the outlet of low pressure relief valve 25 may be connected by a channel 40 to that end of 55 bore 29 containing spring 36 so that liquid exhausted through relief valve 25 may flow therethrough into drain channel 33, and the outlet of relief valve 26 may be connected by a channel 41 to the spring chamber of relief valve 25 so 60 that liquid exhausted through relief valve 26 may flow therethrough and through channel 40 and the left end of bore 29 into drain channel 33.

Low pressure relief valve 25 has its valve member 44 urged toward its seat by a spring 45 the 65 resistance of which may be varied by turning a screw 46 so as to vary the pressure required to open the valve from a predetermined minimum to a predetermined maximum, and high pressure relief valve 26 has its valve member 47 urged to- 70 ward its seat by a spring 48 the resistance of which may be varied by turning a screw 49 so as to vary the pressure required to open the valve from a minimum, which is approximately equal to the maximum pressure required to open 75 valve 25, to a predetermined maximum.

Springs 45 and 48 may be so proportioned that turning screw 46 at a uniform speed will cause the pressure required to open valve 25 to increase at a given rate from a predetermined minimum, for instance 150# per sq. in., to an intermediate value and turning screw 49 at the same uniform speed will cause the pressure required to open valve 26 to vary at the same rate from the intermediate value to a predetermined maximum, for instance 1800# per sq. in., so that the pressure in channel 9 and consequently the pressing force exerted by die 3 is varied at a uniform rate through a predetermined range during a predetermined period of time. 10

It is often desirable that the pressing force 15 be varied at one rate during one part of a pressing operation and at a different rate during another part of the pressing operation. This may be accomplished by so proportioning springs 45 and 48 that turning screw 46 at a uniform speed 20 will cause the pressure required to open valve 25 to increase at a one rate from a predetermined minimum for instance 150# per sq. in., to an intermediate value, for instance 300# per 25 sq. in., and turning screw 49 at the same uniform speed will cause the pressure required to open valve 26 to vary at a different rate from the intermediate value to a predetermined maximum, for instance 1800# per sq. in., so that the pressure in channel 9 and consequently the force 30 exerted by die 3 is uniformly varied at one rate while liquid is being discharged through one relief valve and at a different rate while liquid is being discharged through the other relief valve. 35

In order that the resistances of valves 25 and 26 may be simultaneously varied inversely to each other, screws 46 and 49 may be rotated in opposite directions and have threads of the same hand, or they may be rotated in the same 40 direction and have opposite hand threads.

As shown, screw 46 has a right hand thread and is connected to a shaft 53 which has a driven gear 54 splined thereon, screw 49 has a left hand thread and is connected to a shaft 55 which has a driven gear 56 splined thereon, gears 54 and 56 mesh with a driving gear 57 fixed upon a shaft 58 which is driven through a speed reducer or a reduction gear 59 by a reversible electric motor 60, and all three of these shafts are journaled 50 in a gear case 61 which encloses the gears and restrains them from axial movement.

The arrangement is such that, when motor 60 is energized, gear 57 will rotate gears 54 and 56 at a very slow rate in the same direction and thereby cause one of screws 46 and 49 to gradually advance and increase the tension of one relief valve spring and the other screw to gradually retract and decrease the tension of the other relief valve spring. The resistances of valves 25 and 26 are thus simultaneously varied inversely to each other at a gradual and uniform rate. The individual resistances of relief valves 25 and 26 may be initially adjusted by means of a coupling 62, which connects screw 46 to shaft 53, 65 and a coupling 63 which connects screw 49 to shaft 55.

Current for energizing motor 60 is supplied thereto through a cable 64 from control panel 38 70 to which current is supplied through a cable 65 from a suitable source not shown. Motor 60 is controlled by plurality of manually operable push button switches 66, which are arranged in control panel 38, and by two limit switches 67 and 75

68 which are connected to control panel 38 by cables 69 and 70 respectively.

Switch 67, operation of which causes motor 60 to stop, is arranged in such a position that it is operated by the end of shaft 53 when screw 46 has reduced the resistance of low pressure relief valve 25 to the predetermined minimum. Switch 68, operation of which causes motor 60 to be reversed, is arranged in such a position that it is operated by the end of shaft 55 when screw 49 has reduced the resistance of high pressure relief valve 26 to the predetermined minimum at which time the resistance of low pressure relief valve 25 has been increased to the predetermined maximum.

It is also ordinarily desirable that selector valve 28 be automatically controlled. To this end, control panel 38 is ordinarily so constructed that operation of limit switch 68 by shaft 55 to effect reversal of motor 60 also causes solenoid 37 to be energized and shift selector valve 28 toward the left to the position shown in Fig. 2, and operation of switch 67 by shaft 53 to cause motor 60 to stop also causes solenoid 37 to be deenergized so that spring 36 may shift valve 28 to the position shown in Fig. 1.

Operation

Assuming that the several parts are in the positions shown in Fig. 1, that mold 1 contains a quantity of material to be compressed and that pump 7 is running, the apparatus will function as follows:

Pump 7 will discharge through channel 9, reversing valve casing 11 and channels 17 and 18 into reservoir 8, and piston 5 will be supported by the liquid trapped in the lower end of cylinder 4.

When reversing valve 10 is moved upward to the position shown in Fig. 3, liquid from pump 7 will flow through channel 9, reversing valve casing 11 and channel 20 to the upper end of cylinder 4 and cause piston 5 to move die 3 downward into contact with the material in mold 1, and the liquid expelled from the lower end of cylinder 4 by piston 5 will flow through channel 19, reversing valve casing 11 and channel 18 into reservoir 8.

When die 3 engages the material in mold 1, the resistance thereof will cause pump pressure to rise until it is high enough to raise valve member 44 from its seat and then a part of the liquid discharged by pump 7 will escape through low pressure relief valve 25, thereby limiting the pressure created by the pump and consequently the force exerted by die 3 upon the material in mold 1.

As soon as die 3 starts downward, motor 60 may be started by pressing one of the push buttons in control panel 38. Motor 60 will rotate shafts 53 and 55 through the above described gearing at a very slow rate and thereby cause screw 46 to be advanced and screw 49 to be retracted at a very slow rate.

Screw 46 will gradually and uniformly increase the tension of spring 45, thereby causing a gradual and uniform increase in pump pressure with a resultant gradual and uniform increase in the force exerted by die 3 upon the material in mold 1, and screw 49 will simultaneously decrease the tension of spring 48.

Screw 46 will continue to advance and increase the resistance of low pressure relief valve 25, and screw 49 will continue to retract and decrease the resistance of high pressure relief

valve 26 until the resistances of the two valves are approximately equal at which time the end of shaft 55 will engage the actuating member of limit switch 68 and operate it to thereby cause motor 60 to be reversed and solenoid 37 to be energized and shift selector valve 28 to the position shown in Fig. 2.

Shifting valve 28 to the position shown in Fig. 2 causes communication between relief valve 25 and channel 9 to be blocked so that pump 7 must exhaust its excess liquid through high pressure relief valve 26, and reversing motor 60 causes screws 46 and 49 to be rotated in a direction opposite to their former direction of rotation.

Screw 49 will gradually and uniformly increase the tension of spring 48, thereby causing a gradual and uniform increase in pump pressure with the resultant gradual and uniform increase in the force exerted by die 3 upon the material in mold 1, and screw 46 will simultaneously decrease the tension of spring 45.

Screw 49 will continue to advance and increase the resistance of high pressure relief valve 26, and screw 46 will continue to retract and decrease the resistance of low pressure relief valve 25 until the resistance of valve 26 has been increased to the predetermined maximum and the resistance of valve 25 has been decreased to the predetermined minimum at which time the end of shaft 53 engages the actuating member of limit switch 67 and operates it to thereby cause motor 60 to stop and solenoid 37 to be deenergized and permit spring 36 to shift valve 28 to the position shown in Fig. 1, unless it is desired that die 3 maintain the maximum pressing force upon the material in mold 1 for a given period of time in which case solenoid 37 is not deenergized by limit switch 67 but by a push button which is arranged in control panel 38.

After the material in mold 1 has been compressed, reversing valve 10 is shifted to the position shown in Fig. 4 and liquid from pump 7 flows through channel 9, valve casing 11 and channel 19 to the lower end of cylinder 4 and causes piston 5 to raise die 3, the liquid expelled from the upper end of cylinder 4 by piston 5 flowing through channel 20, valve casing 11 and channels 17 and 18 into reservoir 8.

After die 3 has been raised the desired distance, valve 10 is shifted to the position shown in Fig. 1 and the several parts of the apparatus are in their initial positions and ready to start the second cycle of operation.

The invention herein set forth is susceptible of various modifications and adaptations without departing from the scope thereof as hereafter claimed.

The invention is hereby claimed as follows:

1. The combination, with a hydraulic motor, of a pump, fluid channel means connecting said pump to said motor, means for limiting the pressure created by said pump, said means being adjustable to vary pump pressure between a minimum value and a maximum value and having two parts for causing pump pressure to vary at two different rates, power means, means driven by said power means for gradually adjusting one of said parts to thereby vary pump pressure from said minimum value to an intermediate value at one rate, and means driven by said power means for gradually adjusting the other of said parts to thereby vary pump pressure from said intermediate value to maximum value at another rate.

2. The combination, with a hydraulic motor, of a pump, fluid channel means connecting said

pump to said motor, a low pressure relief valve and a high pressure relief valve connected to said channel means and alternately effective to limit the pressure created by said pump, each of said 5 valves being adjustable to vary its resistance between a minimum and a maximum and said valves being initially so adjusted that the resistance of one is minimum and the resistance of the other is maximum, means for gradually increasing 10 the resistance of one and decreasing the resistance of the other of said relief valves to thereby cause one of said valves to effect a gradual variation in pump pressure from a first to a second value and to simultaneously condition 15 said other valve for operation upon said second pressure valve being reached, and means for blocking communication between said low pressure relief valve and said channel means during the time the resistance of said low pressure 20 relief valve is being decreased.

3. The combination, with a hydraulic motor, of a pump, fluid channel means connecting said pump to said motor, a low pressure relief valve and a high pressure relief valve connected to 25 said channel means and alternately effective to limit the pressure therein, power means, means driven by said power means for simultaneously increasing the resistance of one and decreasing the resistance of the other of said relief valves, 30 means operated by said driven means for reversing said power means, and means for blocking communication between said low pressure relief valve and said channel means during the time the resistance of said low pressure relief valve is 35 being decreased.

4. The combination, with a hydraulic motor, of a pump, fluid channel means connecting said pump to said motor, a low pressure relief valve and a high pressure relief valve connected to 40 said channel means to limit the pressure therein, means for simultaneously increasing the resistance of one and decreasing the resistance of the other of said relief valves, and valve means operable in response to the resistance of said high 45 pressure valve being reduced to a predetermined minimum for automatically blocking communication between said low pressure relief valve and said channel means.

5. The combination, with a hydraulic motor, of 50 a pump, fluid channel means connecting said pump to said motor, a low pressure relief valve and a high pressure relief valve connected to said channel means to limit the pressure therein, means for simultaneously increasing the resistance of one and decreasing the resistance of the other of said relief valves, a selector valve connected between said low pressure relief valve and said channel means, yieldable means and electro-magnetic means for shifting said selector valve 55 into one or the other of two positions in the first of which it establishes communication between said low pressure relief valve and said channel means and in the second of which it blocks communication therebetween, a switch for controlling 60 said electro-magnetic means, and means for operating said switch in response to the resistance of said high pressure relief valve being reduced to a predetermined minimum to thereby cause said selector valve to be shifted to said 65 second position.

6. The combination, with a hydraulic motor, of a pump, fluid channel means connecting said pump to said motor, a low pressure relief valve and a high pressure relief valve connected to said channel means to limit the pressure therein, 70

screw means for adjusting each of said relief valves to vary the resistance thereof, means for simultaneously rotating both of said screw means to cause one to advance and the other to retract and thereby simultaneously increase the resistance of one and decrease the resistance of the other of said relief valves, means for blocking communication between said low pressure relief valve and said channel means during the time the resistance of said low pressure relief valve is 10 being decreased, and separate means for operating said blocking means in response to each of said screws reaching a predetermined point.

7. The combination, with a hydraulic motor, of a pump, fluid channel means connecting said 15 pump to said motor, a low pressure relief valve and a high pressure relief valve connected to said channel means to limit the pressure therein, screw means for adjusting each of said relief valves to vary the resistance thereof, power 20 means, means driven by said power means for simultaneously rotating both of said screw means to cause one to advance and the other to retract and thereby simultaneously increase the resistance of one and decrease the resistance of the other of said relief valves, means operated by 25 said driven means for reversing said power means, and means responsive to operation of said reversing means for blocking communication between said low pressure relief valve and said channel means during the time the resistance of said low pressure relief valve is being decreased.

8. The combination, with a hydraulic motor, of a pump, fluid channel means connecting said pump to said motor, a low pressure relief valve and a high pressure relief valve connected to said channel means to limit the pressure therein, screw means for adjusting each of said relief valves to vary the resistance thereof, means for simultaneously rotating both of said screw means to cause one to advance and the other to retract and thereby simultaneously increase the resistance of one and decrease the resistance of the other of said relief valves, and means operable in response to the screw means for adjusting said 45 high pressure relief valve being retracted to a predetermined point for blocking communication between said low pressure relief valve and said channel means.

9. The combination, with a hydraulic motor, of a pump, fluid channel means connecting said pump to said motor, a low pressure relief valve and a high pressure relief valve connected to said channel means to limit the pressure therein, a first screw means for adjusting said high pressure relief valve, a second screw means for adjusting said low pressure relief valve, a prime mover, means driven by said prime mover for rotating both of said screw means simultaneously to cause one to advance and the other to retract and thereby increase the resistance of one relief valve and decrease the resistance of the other relief valve simultaneously, a selector valve for controlling communication between said low pressure relief valve and said channel means, and means responsive to said first screw means being retracted to a given point for causing said prime mover to be reversed and simultaneously causing said selector valve to block communication between said low pressure relief valve and said channel means.

10. The combination, with a hydraulic motor, of a pump, fluid channel means connecting said pump to said motor, a low pressure relief valve 75

and a high pressure relief valve connected to said channel means to limit the pressure therein, a first screw means for adjusting said high pressure relief valve, a second screw means for adjusting said low pressure relief valve, a prime mover, means driven by said prime mover for rotating both of said screw means simultaneously to cause one to advance and the other to retract and thereby increase the resistance of one relief valve and decrease the resistance of the other relief valve simultaneously, a selector valve for controlling communication between said low pressure relief valve and said channel means, means responsive to said first screw means being retracted to a given point for causing said prime mover to be reversed and simultaneously causing said selector valve to block communication between said low pressure relief valve and said channel means, and means responsive to said second screw means being retracted to a given point for stopping said prime mover.

11. The combination, with a hydraulic motor, of a pump, fluid channel means connecting said pump to said motor, a low pressure relief valve and a high pressure relief valve connected to said channel means to limit the pressure therein, a selector valve for controlling communication between said low pressure relief valve and said channel means, a first screw means for adjusting said high pressure relief valve, a second screw means for adjusting said low pressure relief valve, the threads on one screw means being opposite hand to the threads on the other, a driven gear splined upon each of said screw means, means for restraining said gears from axial movement, a third gear meshing with both of said driven gears, a prime mover for rotating said third gear to cause said driven gears to rotate said screw means and thereby cause them to move axially in opposite directions and increase the resistance of one relief valve and decrease the resistance of the other relief valve, means for reversing said prime mover, and means for shifting said selector valve to cause it to block communication between said low pressure relief valve and said channel means during the time the resistance of said low pressure relief valve is being decreased.

12. The combination, with a hydraulic motor, of a pump, fluid channel means connecting said pump to said motor, a low pressure relief valve and a high pressure relief valve connected to said channel means to limit the pressure therein, a selector valve for controlling communication between said low pressure relief valve and said channel means, a first screw means for adjusting

said high pressure relief valve, a second screw means for adjusting said low pressure relief valve, the threads on one screw means being opposite hand to the threads on the other, a driven gear splined upon each of said screw means, means for restraining said gears from axial movement, a third gear meshing with both of said driven gears, a prime mover for rotating said third gear to cause said driven gear to rotate said screw means and thereby cause them to move axially in opposite directions and increase the resistance of one relief valve and decrease the resistance of the other relief valve, means for reversing said prime mover, and means for shifting said selector valve to cause it to block communication between said low pressure relief valve and said channel means during the time the resistance of said low pressure relief valve is being decreased, said reversing means and said valve shifting means being operable in response to one of said screw means reaching a given point in its axial movement.

13. The combination, with a hydraulic motor, of a pump, fluid channel means connecting said pump to said motor, a low pressure relief valve and a high pressure relief valve connected to said channel means to limit the pressure therein, a selector valve for controlling communication between said low pressure relief valve and said channel means, a first screw means for adjusting said high pressure relief valve, a second screw means for adjusting said low pressure relief valve, the threads on one screw means being opposite hand to the threads on the other, a driven gear splined upon each of said screw means, a means for restraining said gears from axial movement, a third gear meshing with both of said driven gears, a prime mover for rotating said third gear to cause said driven gears to rotate said screw means and thereby cause them to move axially in opposite directions and increase the resistance of one relief valve and decrease the resistance of the other relief valve, means for reversing said prime mover, means for shifting said selector valve to cause it to block communication between said low pressure relief valve and said channel means during the time the resistance of said low pressure relief valve is being decreased, means responsive to one of said screw means reaching a given point in its travel for effecting operation of said reversing means and said valve shifting means, and means for stopping said prime mover in response to the other of said screw means reaching a given point in its axial movement.
